UNITED STATES PATENT OFFICE.

GEORGE E. STACK, OF BALLSTON SPA, NEW YORK, ASSIGNOR TO GENERAL ELECTRIC COMPANY, A CORPORATION OF NEW YORK.

TIME-ELEMENT CONTROL AND APPARATUS THEREFOR.

Application filed May 3, 1923. Serial No. 636,456.

My invention relates to improvements in the control of the operation of various devices by introducing a time interval between the operation of various parts of the devices.

One of the principal objects of the invention is to provide a reliable and inexpensive time element device. Various devices have from time to time been proposed and adopted for obtaining time interval control, such, as for example, dash pots of various types, trains of gears with escapements, trains of gears driven by motors or other constant running devices, etc., but former devices have been expensive when made so as to be reliable. The dash pot, which is usually the least expensive, even when carefully made is not accurate, since the time lag introduced will vary with various conditions, such as temperature, humidity, wear of the parts, etc.

One of the objects of the invention is to eliminate gears, dash pots, and the like, and to reduce the number of the moving parts of the time element device to a minimum consistent with good practice.

A further object of the invention is to provide a time element device which is so simple in construction that the ordinary mechanic or electrician will readily understand the principles involved, so that he may readily adjust the device for the desired time interval.

A further object of the invention is the provision of an improved time element device which is very quickly and easily reset so as to be ready for the next operation in introducing a time lag in the successive operation of various devices.

A still further object of the invention is to provide a device which is so simple and rugged in construction that it is not necessary to protect the device by covers or enclosures, the device being capable of subjecting to the same service and operative conditions as other control apparatus, such as contactors, switches, relays, and the like.

In carrying the invention into effect in one form, I provide electroresponsive means which is arranged to be connected to the member to be controlled so as to alternately hold and release the controlled member and permit the same to move step by step from one position toward another. The electro-

responsive means may take the form of an electromagnet with an armature which is alternately attracted and released in accordance with the frequency of the current supply for the winding of the electromagnet, or the arrangement may be such that the attraction of the armature deenergizes the winding of the electromagnet and the release of the armature again energizes the electromagnet, or the arrangement may take other forms as will be understood by those skilled in the art from an understanding of the invention. The controlled member may be restrained in its movement in a predetermined direction in accordance with the operation of the armature or other movable magnetic member of the electroresponsive device so as to cause the controlled member to proceed in a step by step manner in the desired direction to the predetermined final position.

For a better understanding of the invention, reference is had to the accompanying drawings which show one form of the invention for the purposes of illustration, and in which Fig. 1 is a plan view of a time element device in accordance with the invention controlling an auxiliary switch of an electromagnetic switch or contactor; Fig. 2 is a perspective view of the time element device of Fig. 1; Fig. 3 is a perspective view of a detail of the time element device showing a part of the connections between the controlled auxiliary switch member and the time element device; and Fig. 4 is a very simplified diagram of a time element system of motor control in accordance with the invention.

Referring to the accompanying drawings, the time element device 10 is indicated as an auxiliary switch which is controlled by the main electromagnetic switch mechanism comprising the operating electromagnet 11 with its movable armature 12 connected to the switch shaft 13 on which movable contacts 14, 15 and 16 are mounted so as to be simultaneously operated. The blowout arc chutes 17, 18 and 19 are provided for disrupting the arcs formed between the movable contacts 14, 15 and 16 and their respective stationary contacts. The switch mechanism 14, 15 and 16, the common operating shaft 13, and the electromagnetic operating means comprising the operating magnet 11

with its operating armature 12 form a well known construction and one which will be readily understood by those skilled in the art without further description.

5 The time element device 10, which is shown in more detail in Fig. 2, comprises a pivotally mounted movable switch member 20 which is biased by gravity to the open position and is operated to the closed position by a pull transmitted through the operating shaft 13. The arm 21 connected to the shaft 13 is arranged so as to cooperate with an adjusting nut (not shown) mounted on the screw thread rod 22 for the purpose 10 of applying a force through the spring 23 to urge the switch member 20 to the closed position. The spring 23 has one end thereof connected to the screw thread rod 22, and the upper end thereof is hooked in the 15 hole 24 in the kicked-up end of the switch member 20 as indicated in Fig. 3.

The movement of the switch member 20 to the closed position is retarded by means 20 of the timing arrangement which I shall now describe. The arm 25 is connected to the switch member 20, as shown in Fig. 3, and one end of this arm carries a movable magnetic member or armature 26 of an electromagnet which is provided with a coil 27 disposed on a core 28. The armature 26 is mounted in the one end of the arm 25 in such a manner that the armature is capable of a relative movement with respect to the arm, and thus with respect to the switch member 20, and yet the armature is carried along by the arm 25 when the arm is released by the armature. The armature 26 is provided with a projection 29 which projects through a suitable opening in the arm 25 so as to interlock the armature with the arm. The arrangement is such that when the switch member 20 is urged to the closed position by reason of the force applied through the spring 23 from the shaft 13, the arm 25 will be momentarily held by the armature 26 because of the fact that this armature will be attracted to the end of the pole 28 of the electromagnetic timing device. It is presumed that the coil 27 of the 40 timing electromagnet is connected to an alternating current supply circuit, so that the magnetism of the core 28 will be periodically reversed in accordance with the frequency of the supply circuit. This will cause a 45 chattering of the armature 26; that is, the armature 26 will be periodically attracted and released in a definite periodicity in accordance with the frequency of the supply circuit. While the armature is attracted, it will magnetically hold the arm 25, and thus the switch member 20, and when the armature is released, the arm 25 will be 50 permitted to move a short distance until the armature is again attracted. The armature is thus caused to skip in a substantially

definite periodic step by step manner over the pole piece 28, periodically holding and releasing the arm 25.

The time lag between the closing of the main switch contact mechanism 14, 15 and 70 16 and the closing of the auxiliary switch contact mechanism will be determined by the length of time required for the armature 26 to skip over the end of the pole piece 28 in the manner previously described. This 75 time may be easily adjusted by turning the adjusting screw 30 so as to vary the initial position of the arm 25. It will be observed that the movement of the switch member 20 to the closed position would be a continuous and uninterrupted movement if it were not for the timing device, but with this timing device the movement of the switch member is changed into a step-by-step movement of a substantially definite periodicity and the number of steps in the movement may be very easily adjusted by turning the adjusting screw 30. Thus by turning the adjusting screw 30 so as to move the switch member 20 and the arm 25 in 80 a counter-clockwise direction about the pivotal support for these members, the time lag introduced and the number of steps in the step-by-step operation will be reduced, but if the adjusting screw 30 is turned in 85 the opposite direction, the time lag introduced will be increased.

It will be observed that while I have shown my invention in connection with an arrangement intended primarily for use on alternating current circuits, I would have it understood that the invention is not necessarily limited to an alternating current device, and may be applied to a direct current system as well, it merely being necessary to 105 provide some suitable means for interrupting the current in the magnet winding 27 in accordance with the attraction of the armature 26 and to reenergize this winding in accordance with the release of the armature 26 so as to thus obtain a substantially definite periodicity of the step by step advance of the armature and switch member. Such a modification will be well understood by those skilled in the art, and it is believed 110 that a further description is unnecessary.

Referring to Fig. 4, it will be seen that I have disclosed my invention in connection with an arrangement for starting an alternating current three-phase wound rotor type 120 of electric motor. Referring to the figure, the electric motor M is arranged to be connected to the alternating current supply circuit by means of the electromagnetic line switch or contactor 31. The master switch 32 is provided for controlling this line contactor and the accelerating contactors 33 and 34, as well. When the line contactor 31 closes, it puts the auxiliary switch member 20 under a bias to the closed position, but 125 130

- this switch member is retarded in its movement to the closed position by means of the time element device previously described, the coil 27^a of the time element device being 5 simultaneously energized with the energization of the winding of the line contactor 31. The auxiliary switch member 20^a will skip or move step by step toward the closed position in an interval of time which may be predetermined, and when the switch member makes engagement with its stationary contact, the accelerating contactor 33 is energized to close so as to short circuit the resistors R¹ in the rotor circuit of the motor. 10 15 When the accelerating contactor 33 closes, it places the auxiliary switch member 20^b under a strain to the closed position, but this switch member is restrained in the manner previously explained. After the switch member 20^b has moved step by step to the closed position, the accelerating contactor 34 is energized to close and short circuit the resistors R² and thereby connect the motor for full speed operation. 20 25 It will be observed that my time element device is very simple and rugged in construction and has relatively few parts, which are easily made. It will also be observed that the time element device as a whole is of the same nature as the switch mechanism with which it cooperates, so that this time element device does not need to be protected by a cover, or by an enclosure; and it will also be noted that the device is very easily adjusted. 30 35 When the main switch contacts with which the time element device is associated are opened, the auxiliary switch of the time element device will move directly to the full open position, since its movement in this direction is unrestrained and the device will be immediately reset for the next operation.
- In accordance with the provisions of the patent statutes, I have described the principle of my invention, together with the apparatus which I now consider to represent the best embodiment thereof but I desire to have it understood that the apparatus is only illustrative and that the invention can be carried out by other means.
- 50 What I claim as new and desire to secure by Letters Patent of the United States, is,—
1. A time element device comprising a controlled member which is urged from one position toward a second position, and electroresponsive means having two relatively movable parts, one of which is carried by the said member and cooperates with the other part to alternately magnetically hold and release the said member and permit the member to move continuously forward in a step by step manner to the said second position when released and thereby introduce a substantial time interval before said controlled member reaches the second position.
  - 60 65 2. A time element device for retarding the

action of a controlled member which is urged from one position toward a second position, comprising electroresponsive means having a magnetic movable member which is alternately magnetically held and released and which is carried by the said controlled member to alternately hold and release the same and permit the controlled member to move forward continuously step by step toward the said second position in accordance with the release of the magnetic movable member and thereby introduce a substantial time interval before said controlled member reaches the second position.

3. A time element device comprising a controlled member which is urged from one position toward a second position, an electromagnet having a core and a magnetic movable member which is alternately attracted to and released from the said core, and connections between the said magnetic member and the said controlled member whereby the said members move in a step by step succession of continuous forward movements with reference to the said core in accordance with the release of the magnetic member and thereby introduce a substantial time interval before said controlled member reaches the second position.

4. A time element device comprising a controlled member which is urged from one position toward a second position, an electromagnet having a core and an armature which is connected to the said member to be moved thereby across the end of the said core and impart a step by step continuous forward movement to the said member as the armature is attracted to and released from the said core, whereby a substantial interval of time is introduced in the movement of the member from the first position to the second position.

5. A time element device comprising a pivotally mounted control member which is urged to move in one direction about its pivot from one position to a second position, an electromagnet having an armature which is alternately attracted and released, and connection between the said armature and the said controlled member whereby the said member and the armature move in a succession of step by step forward movements about the pivot of the member in accordance with the attraction and release of the armature to thereby introduce a substantial interval of time in the movement of the member to the said second position.

6. A time element device for electric switches comprising a switch member, and means for urging said member from one position to a second position, an electromagnet having an armature which is alternately attracted and released and which is connected to the said switch member to alternately restrain the movement of the switch

- member in response to the urge of said means and permit the switch member to advance step by step from the first position toward the second position as the armature is attracted and released, whereby a substantial interval of time is introduced in the movement of the switch member from the first to the second position.
7. An electric switch comprising an operating electromagnet, main switch contact mechanism operated thereby, an auxiliary switch which is urged toward the closed position by the said operating electromagnet, and a restraining electromagnet for delaying the closing of the auxiliary switch for a definite interval of time after the operation of the said main switch contact mechanism, the said restraining electromagnet having an armature which is alternately attracted and released and is connected to the said auxiliary switch to impart a step by step movement thereto as the armature is attracted and released.
8. An electric switch comprising main switch contact mechanism, an operating electromagnet therefor, an auxiliary switch, a resilient connection between the auxiliary switch and the operating electromagnet through which force is applied to close the auxiliary switch, and means for delaying the closing of the auxiliary switch a definite interval after the closing of the main switch contact mechanism, comprising an electromagnet having a magnetic movable member which is alternately attracted and released and is connected to the said auxiliary switch to cause the same to move step by step to the closed position in accordance with the attraction and release of the magnetic movable member.
9. A time interval device for controlling electric circuits comprising an electromagnet having an armature which is alternately attracted thereto and released therefrom in a definite periodicity when the winding of the electromagnet is energized by a current which increases and decreases in a definite periodicity, a switch contact movable between two positions, a device connected with said contact for urging the contact to move immediately from the first of said positions to the second thereof, and a mechanical connection between the said contact and said armature permitting of movement of the armature with respect to the contact whereby when the contact is urged by said device from the first of said positions to the second thereof the said contact is alternately restrained and released by the armature with a definite periodicity as the contact advances in response to said urge so that an appreciable time interval is introduced before the contact reaches said second position.
10. A time interval device for electric circuits comprising an electromagnet having a core and an armature which is alternately attracted to and released from the core in a substantially definite and constant periodicity, a switch member connected to said armature to be restrained thereby in moving from one position to a second position, the connection between the switch member and the armature permitting relative movement of the armature with respect to the switch member, whereby when the switch member is urged to move directly forward from the first position to the second position the said armature modifies the direct forward movement into a succession of step-by-step forward movements of a definite and constant periodicity as the armature is attracted to and released from said core to thereby introduce a substantial time interval before the member reaches the second position.
11. An electric switch having main switch contact mechanism, an operating electromagnet therefor, an auxiliary switch, a resilient connection between said electromagnet and said switch through which force is applied to close the switch when the electromagnet is energized to close said contact mechanism, a retarding electromagnet for said auxiliary switch having a stationary core with a winding disposed thereon and a movable armature which moves across one end of said core and is connected with said auxiliary switch to move with respect thereto as the armature is alternately attracted to and released from said core, whereby a delayed step by step movement of said auxiliary switch to the closed position is effected.

In witness whereof, I have hereunto set my hand this 2nd day of May, 1923.

GEORGE E. STACK.
